UNITED STATES PATENT OFFICE

DANIEL I. ROGERS, OF NEW HAVEN, CONNECTICUT, ASSIGNOR TO THE G & O MANUFACTURING COMPANY, OF NEW HAVEN, CONNECTICUT

RADIATOR-MAKING MACHINE

Application filed January 21, 1927. Serial No. 162,580.

This invention relates to the so-called fin and tube radiators, and more especially relates to an improved machine for making or forming the fins and assembling them upon 5 the tubes used in making such a radiator.

The machine of this invention is similar to the machine described and claimed in a co-pending application, Serial No. 1062, filed January 17, 1925, in so far as the methods 10 used and certain features common to both are concerned, but is generally an improvement thereover in that new and useful features have been combined with the novel features thereof to form, with respect to the 15 ease and economy of operation, and quality of the product therefrom, a more efficient machine.

The machine of this invention is substantially automatic in its operation, thereby requiring only a minimum amount of attention 20 from an operator. In this machine, the fins are fabricated, collected substantially as soon as fabricated, arranged in spaced relation to each other, forced upon a tube and removed 25 with the tube from the collecting device in substantially a continuous and automatic action on the part of the machine.

One of the objects of this invention is to provide a machine having the parts thereof 30 cooperating in such a manner that a series or group of fins will be fabricated, collected and assembled upon a tube to form a radiator unit both economically and efficiently.

Another object of this invention is to provide a machine wherein the fin collecting means is advanced by power in one direction while collecting the fabricated fins, and is returned by power to its initial position after a predetermined period in the operation of 40 the machine.

Another object of this invention is to provide in such a machine, means to insure the passage of the fabricated fins without delay into the collecting means.

A further object of this invention is to provide, in a machine of this type, an improved form of fin collecting means.

A still further object of this invention is to provide, in a machine of this type, an improved form of tube retaining means.

Still another object of this invention is to provide, in a machine of this type, means to automatically release the tube from the action of the tube retaining means.

Still another object of this invention is to 55 provide improved means for feeding the fin collecting means during the operation of the machine.

A still further object of this invention is to 60 provide improved interconnecting means between the operable parts of a machine of this type.

A further object of this invention is to 65 provide, in a machine of this type, means to raise the collected fins, after the same have been assembled upon a tube, out of the fin and tube retaining members of the machine.

A still further object of this invention is to 70 generally improve the structure and operation of a machine of this type.

To these and other ends, the invention consists in the novel features and combinations of parts to be hereinafter described and claimed.

In the accompanying drawings: 75

Fig. 1 is a front elevation of a machine embodying the features of this invention;

Fig. 2 is a left hand side elevation of the same;

Fig. 3 is a section on line 3—3 of Fig. 1; 80

Fig. 4 is a right hand side elevation of the machine;

Fig. 15 is a section on line 15—15 of Fig. 1;

Fig. 16 is a section on line 16—16 of Fig. 1;

Fig. 17 is an enlarged section somewhat similar to Fig. 6, showing the arrangement of a tube and fin in the collecting means; 100

Fig. 18 is a side view of the parts shown in Fig. 17;

Fig. 19 is a section on line 19—19 of Fig. 15; and

5 Fig. 20 is a continuation of Fig. 19.

The machine illustrated in the drawings is generally in the form of a punch press, where-in a base 20 is supported upon legs 21 and having a frame extending upwardly therefrom, consisting of side uprights 22 and 23. A crank shaft 25 is journaled in the uprights, with its crank portion 26 intermediate the same. A power driven fly wheel 27 is rotatably mounted upon one end of the shaft 25, being operably connectible thereto in a common manner by a suitable normally open spring operated clutch mechanism (not shown), but operable upon releasing a catch by the lowering of a rod 28 by means of the usual hand lever 29. A pitman 30 is rotatably mounted upon the crank portion 26, and is suitably secured to a reciprocating gate 31, which is guided in its reciprocating movements, by the cooperation of the guides 32 thereon, with guideways 33 formed upon the uprights 22 and 23. Rotation of the shaft 25 causes reciprocation of the gate 31 toward and from the base 20 in the usual manner. A disk 34 is mounted upon the other end of the shaft 25 and is disposed without the adjacent uprights 23. Intermediate the disk 34 and the adjacent upright, an eccentric portion 24 is formed upon the shaft 25.

35 A punch block 35 containing a suitable set of punches for fabricating a fin for a radiator unit of a fin and tube radiator is secured to the underside of the gate 31. The punches cooperate with a set of dies mounted in a die block 36, secured upon the bed or base 20. In this instance, sufficient punches and dies are provided so that three fins are fabricated simultaneously, the fins dropping, partly due to gravity, as soon as fabricated, through suitably formed openings 37 in the die block 36 into chutes 38.

40 A coil or other source of supply of material 39, suitable for fins, is provided and mounted upon a bracket 40 at one side of the machine. The material 39 is fed over the dies beneath the punch by means of a pair of feed rolls 41 disposed at the side of the machine opposite to the coil of material 39, and which operate to exert a pull upon the material. The upper roll of the 45 pair of rolls 41 is arranged in bearings in such a manner that the same may be raised out of contact with the strip of material by the engagement of a lever 43 secured thereto, with an adjustable stud 44 mounted upon the 50 gate 31. This roll and the bearings, therefore, are raised at each downward stroke of the gate 31 so as to allow the strip of material 39 to remain stationary during the interval that the punches and dies are operating thereon to fabricate a fin or fins.

In this instance, the strip of material is fed intermittently by the rolls 41, they being rotated intermittently by the cooperation of a ratchet and pawl mechanism 45, the ratchet wheel of which is secured to the lower roll 70 which is geared to the upper roll by the gear train 46. The pawl member of the mechanism 45 is operated by a rod 47 secured to a lever arm 48, mounted upon the end of a rock shaft 49, secured upon the upright 75 23. The rock shaft is rotated by a rod 50, secured at one end to an arm 51, secured upon the other end of shaft 49, and at the other end to a stud 52 eccentrically and adjustably mounted upon the outer face of the disk 34. 80 By proper adjustment of eccentricity between the stud 52 and the disk 34, the pawl and ratchet mechanism 45 will operate to feed the strip of material a sufficient amount during the nonoperating stroke of the punches to present beneath the same a required amount of material from which to form a fin or fins. Secured to the shaft of the upper roll of the feed rolls 41, is a pulley 53 which, by a belt connection with a pulley 54 drives a takeup 85 device 55 upon which the scrap stock, not used in making the fins, is collected.

90 Guided by the chutes 38, the fins are received in a rack 60, being collected, arranged in spaced relation relative to each other, and 95 retained therein, while a tube is being forced therethrough. The rack 60 is provided with a series of vertically disposed pockets 61, which are of a depth and width substantially equal to the corresponding dimensions of the 100 fins, and which are spaced apart longitudinally with respect to the rack the desired amount at which the fin will be disposed upon the tube. The rack 60 is slidably supported in a guide 62 by the cooperation of the clove-tailed 105 shaped sides 63 thereof with corresponding grooves in the guide 62. The guide 62 is secured to the machine by means of brackets 58 and 59, and with the rack is disposed below the bed or base 20. A toothed gear rack 64 110 is secured to the underside of the rack 60, with which a pinion 65 meshes, and by the rotation thereof slides the rack 60 relatively to the guide 62. A pair of racks 64 and pinions 65 are provided in this instance. 115

120 At a plurality of points longitudinally of the rack, there is provided means to raise the assembled fins and tubes therefrom. Suitable openings in the rack 60 allow an arm 66 of a member 67 to be raised into engagement with the bottom edge of the fins. In this instance, three of such arms 66 are provided upon each member 67. Secured to the lower surface of the member 67 is a downwardly extending bracket 68 upon which is mounted 125 a roller 69. In a slot 70 formed in the under surface of the rack 60 is a longitudinally slidable bar 71. The bar 71 is provided with a series of camming surfaces 72 formed upon upwardly extending lugs 73 thereon. The 130

camming surface 72 is adapted to engage the rollers 69 of each member 67, when the bar 71 is moved in one direction to cause the members 67 to raise simultaneously whereby the arms 66 thereof will engage the assembled fins and tubes to raise them out of the rack, facilitating the removal thereof by the operator.

The pinion or pinions 65, are securely mounted upon a shaft 74 journaled in bearings 75 upon the guide 62. A gear 76 is secured to an end of the shaft 74. In this instance, one at each end is provided each of which meshes with a pinion 77 securely mounted upon a shaft 78. A pawl and ratchet wheel mechanism having the ratchet wheel 79 thereof secured upon the shaft 78, is provided to rotate the same by the action of the pawl 80 thereof. The pawl 80 is mounted upon a rocking lever 81 pivoted upon the outer end of the shaft 78, and is suitably urged toward the ratchet wheel 79 by a spring in the usual manner. The rocking lever 81 is operably connected to one end of a rocking arm 82, which is pivoted to the upright 23 at 83 by a rod 84. The other end of the arm 82 is secured to an eccentric ring 85 rotatably mounted upon the eccentric portion 24 of the crank shaft 25. A locking pawl 86 is provided which is pivoted to the guide 62 at 87 and suitably urged toward the ratchet wheel 79 by spring means in the usual manner to engage the teeth thereof to prevent backward rotation thereof. The rotation of the eccentric portion 24 will cause the rack 60 to intermittently feed in one direction while the fins are being fabricated. The gearing above described is so proportioned that the rack 60 will be fed in this direction in timed relation to the action of the punches and dies, whereby a pocket 61 will be presented directly beneath the corresponding chute 38 to receive a fin as soon as it is fabricated.

Means is provided to insure a rapid movement of the fabricated fins toward the rack 60 and to prevent them from rebounding and interfering with the action of the machine when the same is being rapidly operated. A tube 90 is provided and disposed in each chute 38. Openings 90^a directed downwardly toward the rack 60 are provided in the tube 90. A supply pipe 91, communicating with tubes 90, provides a passage for compressed air when the same is used. A valve 92 controls the flow of the compressed air through pipe 91 and tube 90. The air then flows out of the openings 90^a in a steady stream which engages the fins as they drop into the chute 38 and rapidly forces them downwardly toward the rack 60. An end opening 90^b in the tube 90 permits the flow of air to engage the fin as it enters a pocket 61 and prevents it rebounding therefrom.

A lock bar 95 is connected to the lower end 65 of the clutch operating rod 28 and extends

downwardly therefrom into a lock box 96 wherein it may vertically slide. At its lower end, the bar 95 is provided with locking notches 97 and 98, the notch 97 forming a downwardly directed shoulder 99, and the notch 98 forming an upwardly directed shoulder 100. A horizontally slideable bar 101 is guided in a slot in the box 96 and by a bracket 102. The bar 101 is provided at one end with an inwardly directed notch engaging member 103, and with an outwardly directed extension 104. A coil spring 105 tends to urge the bar 101 to cause the member 103 to enter the notch 98 and engage the shoulder 100 when the lock bar 95 is moved downwardly by the handle 29. A lock bar retaining rod 106 is also horizontally slideable in the bracket 102 and in a portion of the box 96. The rod 106 is provided with a notch engaging end 107 adapted to enter the notch 97 and by engagement with the shoulder 99 to retain the bar 95, and through it the hand lever 29, and clutch mechanism, in clutch released position. The rod 106, in this instance, is manually operable and provides an accessible means whereby the machine can be locked in non-operating position, so that the same will not be inadvertently started. A gravity actuated catch 108 engages the rod 106 in a suitable recess 109, to retain the rod in locked position.

The bar 101 upon being moved into a position to release the member 103 from engagement with the shoulder 100, allows the lock bar 95 to move upwardly whereby the clutch mechanism will be operated into its normal open position, and the fly wheel 27 will rotate idly without operating the machine. The bar 101 is connected to an arm 110 of a rocking sleeve 111, rotatably mounted upon a bracket 112, and having a downwardly projecting pawl 113 thereon. Rotation in one direction of the sleeve 111 to rock it, causes the arm 110 to slide the bar 101 in a direction whereby the member 103 is released from engagement with the shoulder 100. A pawl engaging lug 114 is mounted upon the rack 60, and disposed in proper position thereon to engage the pawl 113 and thereby to rock the sleeve 111 when the rack is in a predetermined position of its forward sliding movement.

In timed relation with the engagement of the pawl 113 and the lug 114, a member 115 secured to the rack 60 engages a lug 116 secured to a slideable bar 117, mounted upon the guide 62. The bar 117 is provided with pawl engaging members 118 and 119, which engage respectively the pawls 80 and 86 to release them from engagement with the ratchet wheel 79.

Continued forward movement of the rack 60 is, in this instance, desired, as will appear hereinafter, and therefore, the operator of the machine manipulates the hand lever 120, which is pivoted to the base 20 and oper-

ates a toothed clutch mechanism 121. This action connects a forwardly rotating power driven pulley 122, which is freely rotatable upon a hollow shaft 123, with the shaft, one portion of the clutch mechanism 121 being secured thereto and the other forming a part of the pulley 122 (see Fig. 8). Movement of the hand lever 120 slides a clutch operating rod 124 through the hollow shaft 123, and due to the connection 125 between the rod 124 and the shidable clutch member, moves the same. A shifting sleeve 126 is likewise secured to the rod 124, and by means of arms 127 is connected to a transversely slidable control bar 128, which is slidably retained at the rear of the machine in brackets 129. A gear 130 is keyed or otherwise secured to the hollow shaft 123 and is in mesh with an idler pinion 131, which in turn is in mesh with a gear 132, secured to shaft 74. Rotation of the hollow shaft 123 by pulley 122 will, therefore, feed the rack 60 forwardly in a continuous movement.

At a predetermined point in the continuous forward feed of the rack 60, it is again stopped due to the engagement of an adjustable stop member 133, with a lug 134, mounted upon a bar 135, slidably mounted upon the guide 62. A cam lug 136 is positioned upon the bar 135 to engage at a predetermined time an arm 137 of a bell crank, the other arm 138 of which is in engagement with a stud 139 projecting from the control bar 128. When the cam lug 136 engages the bell crank arm 137, the bell crank is rocked whereby the control bar 128 will be shifted, and by moving the shifting sleeve 126, will release the clutch mechanism 121, thereby interrupting the connection between the pulley 122 and the hollow shaft 123 to stop the forward feed of the rack 60.

A tube supporting mechanism is secured to the forward end of the guide 62, and which cooperates with the rack 60, and its associated parts during their forward sliding movements. A tube retaining and supporting rod 140 is slidably mounted in a block 141, which is slidably mounted upon a base 156. The rod 140 is directed inwardly toward the forward end of the rack through a tubular member 142, from which it projects a sufficient amount to support a tube, and to space it longitudinally from the block 141. The arrangement is such that a tube 143 may be slipped over the projecting end and held thereby, extending along a longitudinally extending groove 144 in the rack 60. The groove 144 provides clearance for a flange 145 about a central opening in the fin 146, as well as clearance for the disposition of the tube 143 in proper position to enter the opening in the fin 146. In this instance, three rods 140 are provided whereby three tubes 143 may be supported in corresponding grooves 144 in the rack 60. The rod or rods 140 are secured at one end to a plate

147, which is retained against the forward surface of the block 141, by means of a compression spring 148. Another rod 149 extends inwardly toward the rack 60 below the rod or rods 140, and in alignment with an unslotted portion of the rack, so that the same will be engaged thereby when the rack reaches a predetermined point in its forward movement. Upon engagement of the rack 60 with the rod 149, the same with the plate 147 and the rod or rods 140 is forced forwardly whereby the projecting end of the rod 140 is withdrawn from the tube 143. A continued forward feed of the rack 60 causes the forward end of the same to engage another rod 150 which extends through the block, with its forward end secured to a plate 151, which is urged into engagement with the forward surface of the block by a compression spring 152.

The rod 150 is provided with a camming notch 153, disposed within the block 141, the camming surface of which engages a member 154 of a pin tumbler mechanism. Another member 155 of this mechanism is vertically slidable in the supporting base 156, being urged upwardly by a spring 157, so as to retain the joint between the two members 154 and 155 above the lower surface of the block 141, and above the upper surface of the base 156, so that the two parts, block 141, and base 156, are retained against relative movement. By aligning the joint between the members 154 and 155 with the joint between the surfaces of the block 141 and base 156, the block 141 is released and under the urge of the spring 148, will be pulled forwardly, the spring 148 being under tension due to engagement of the rack 60 with the rod 149. This action causes the block and its associated parts to be removed from the immediate neighborhood of the rack whereby the fins and tubes in the rack are free to be raised therefrom without the possibility of being interfered with by any overhanging parts. In this instance, two rods 150 with their associated parts have been provided.

A rod 160 is secured to the forward end of the bar 71, and projects forwardly from the forward end of the rack 60, being slidable therethrough. During the last period of the forward feed of the rack 60, the rod 160 engages against the rear surface of the base 156 and is pressed inwardly. This action moves the bar 71 rearwardly, thereby causing the camming surfaces 72 to engage the rollers 69, whereby the fin and tube raising means is operated to raise the same out of the rack 60, whereupon the operator may readily remove the same from the machine.

By proper manipulation of the hand lever 120, a clutch member 161 (see Fig. 8) is engaged with a cooperating clutch member 162 formed in a pulley 163, freely rotatable upon the hollow shaft 123 to connect the same there-

to. The rotation of the pulley 163 is the reverse of that of the pulley 122, so that the rack 60 may now be moved continuously rearwardly toward its initial fin receiving position. As the rack 60 approaches its predetermined initial position, an adjustable stop member 164 engages the lug 134 on the bar 135 to reset it into its other position, and a camming lug 165 secured to the rack 60, engages a roller secured to a depending arm 166, forming part of the control bar 128. The engagement of the lug 165 with the arm 166 shifts the shifting sleeve 126, and by it the clutch member 161, out of engagement with the corresponding part 162 to disengage the pulley 163 from the shaft 123 to stop further feed of the rack 60 in a rearward direction.

As the rack 60 approaches its initial position, a rod 167 projecting from the rear end of the bar 71 and through the corresponding end of the rack 60, engages against an adjustable stop member 168, secured to the rear end of the guide 62. The engagement of the rod 167 with the stop 168 presses in the rod 167 and slides the bar 71 forwardly, whereby the fin and tube raising means is lowered and the rack 60 is in condition to receive and collect fins from the fabricating means into all of its pockets 61 thereof.

The control bar 128 is provided with a notch 170, into which a spring pressed pin 171 mounted upon the base 20 in a bracket 172 is adapted to seat. The notch 170 is located in proper position lengthwise of the bar 128 so that when the pin 171 is seated therein, both clutches will be in inoperative position. A neutral position of the control bar 128 is, therefore, provided and the bar is retained in such position against inadvertent movement in either direction, due to vibration or the like, by the cooperation of the pin 171 and the notch 170.

The operation of the machine although obvious from the above description of the cooperating parts thereof, generally is as follows. A supply of fin material 39 together with a supply of tubes 143, is provided. The machine is set with the rack 60 positioned with its forward end below the dies and beneath the base 20. A tube 143 is placed upon the projecting ends of each of the rods 140, and power is applied to the crank shaft 25.

As soon as rotation starts, the feed rolls 41 act upon the strip of material to feed it between the punches and dies, and the punches descend and fabricate fins 146. The fins drop through openings 37 in the die block and are rapidly forced through chutes 38 into the pockets 61, of the rack 60, by the compressed air blast from the openings 90^a and 90^b of the air tubes 90. The rack 60 is fed forwardly at each stroke of the machine, to present an empty pocket 61 below a chute to receive the next fabricated fin. As the rack 61 with the fins 146 therein advances toward the tube 143,

the latter enters the openings in the fins 146 and is forced therethrough, whereby the fins are assembled upon the tube in the required spaced relation with each other.

When the desired number of fins have been fabricated and assembled upon the tube by the operations of the cooperating machine elements, the movements of the racks and the fabricating means are automatically stopped. The operator then manipulates the hand lever 120 to provide a continuous forward feed to the rack, which again advances toward the block 141 located at the forward end of the machine.

At a predetermined period in its forward movement, the rack by engagement with the rod 149 releases the tube supporting rods and withdraws them from the tubes. A further advance of the rack in the same direction releases the block 141 from the base 156, as above described. Substantially simultaneously with the forward movement of the block 141 and release of the same from the base 156, the pin 160 operates to cause the bar 71 to raise the assembled fins and tube from the rack 60. At this period of the machine operation the feed of the rack is again automatically interrupted by the engagement of the lug 136 with the arm 137 of the bell crank, which operates the control bar 128 and releases the clutch 121.

By manipulation of the hand lever 120 in the other direction, the rack is provided with power whereby it is moved rearwardly into its initial position below the dies for the reception of newly fabricated fins. As it nears the termination of its rearward feed the bar 71 is reset into its initial position, whereby the fin raising means is lowered and the rearward feed of the rack is interrupted by the engagement of lug 165 with the arm 166, which operates the control bar 128 to release the clutch parts 161 and 162 from engagement. At substantially the same time that the feed is interrupted the control bar 128 is moved into its neutral position with the pin 171 seated in the notch 170. Manipulation of the bar 117 to slide it rearwardly permits the engagement of pawls 80 and 86 with the ratchet wheel 79 whereby intermittent forward feed of the rack 60 may be obtained. By supplying additional tubes, the machine may be again operated to fabricate and to assemble fins thereon as above described.

The strip of fin material 39 is arranged in the machine illustrated, so that it moves transversely to the direction of movement of the rack 60, which in this instance, moves longitudinally with respect to the forward and rear portions of the machine. The movement of the control bar 128 is also transverse to the direction of movement of the rack and the movement of the pawl control bars and continuous rack feed control bar, are in the same direction as the rack in the machine

illustrated. Although the direction of movement of the above parts has been described as illustrated, deviation therefrom is possible under certain conditions.

5 I do not claim herein the broad combination of means to fabricate radiator fins or plates, means to collect the fins or plates as fabricated, and means to assemble them upon a tube, or the method of making a radiator 10 unit or the detailed features thereof as shown, described and claimed in my copending application, Serial No. 1,062, filed January 7, 1925.

15 While I have shown and described a preferred form of machine, it is to be understood that I do not limit myself to all of the details and structure, or combinations thereof as shown, as the same may be modified and varied and still lie within the spirit of 20 the invention and the scope of the appended claims.

What I claim is:

25 1. In a machine for assembling radiator elements upon a support, means to receive a number of the elements, means to hold the support upon which the elements are to be assembled, means for advancing the element receiving means towards the support to assemble the elements thereon, and means operable by a continuation of the movement of 30 said last named means for automatically ejecting the elements and the support from said receiving means when the elements are assembled on the support.

35 2. In a machine for assembling radiator elements upon a support, means to receive a number of the elements, means to hold the support upon which said elements are to be assembled, means for advancing the element receiving means toward the support to assemble 40 the elements thereon, automatic means for releasing the support from its holding means, and automatic means operable by a continuation of the movement of said last named means for ejecting the elements together with the support from the element receiving means upon the release of the support from its holding means.

45 3. In a machine for assembling radiator elements upon a support, means to receive a number of the elements, means to hold the support upon which the elements are to be assembled, means for advancing said element receiving means towards said support to assemble the elements thereon, and means controlled by the movement of said element receiving means for ejecting the elements from 50 said element receiving means.

55 4. In a machine for assembling radiator elements upon a support, means to receive a number of the elements, means to hold the support upon which the elements are to be assembled, means for advancing said element receiving means towards said support to assemble 60 the elements thereon, means con-

trolled by the movement of the element receiving means for releasing said support from its holding means, and means controlled by said movement for ejecting said support together with the elements assembled thereon 70 from element receiving means.

5. A machine for making radiator units comprising means to fabricate an element of said unit, means to collect and retain a number of said elements, means to hold another element of said unit, power driven means to move said collecting means intermittently toward said element holding means to assemble said elements together, means to interrupt the intermittent movement of said 80 collecting means, and power driven means to move said collecting means in a continuous movement in the same direction upon the interruption of said intermittent movement.

6. A machine for making radiator units comprising means to fabricate an element of said unit, means to collect and retain a number of said elements, means to hold another element of said unit, power driven means to move said collecting means intermittently toward said element holding means to assemble said elements together, means to interrupt the intermittent movement of said collecting means, and power driven means to move said collecting means in a continuous movement 90 in the same direction upon the interruption of said intermittent movement, and power driven means to return said collecting means to its initial position.

7. A machine for making radiator units comprising means to fabricate an element of said unit, means to collect and retain a number of said elements, means to hold another element of said unit, power driven means to move said collecting means intermittently toward said element holding means to assemble said elements together, means to interrupt the intermittent movement of said collecting means, and power driven means to move said collecting means in a continuous movement 100 in the same direction, upon the interruption of said intermittent movement, said last mentioned means being operable to return said collecting means to its initial position.

8. A machine for making radiator units comprising means to fabricate an element of said unit, means to collect and retain a number of said elements as the same are fabricated, means to hold another element of said unit, power driven means to drive said fabricating means and to move said collecting means toward said element holding means, means to interrupt said driving means, power driven means adapted to be connected to said collecting means to move it toward said holding means upon the interruption of said first mentioned power means, said last named power driven means being operable to return said collecting means to its initial position.

9. A machine for making radiator units 130

- comprising means to fabricate an element of said unit, means to collect and retain a number of said elements as the same are fabricated, means to hold another element of said unit, power driven means to drive said fabricating means and to move said collecting means toward said element holding means, means to interrupt said driving means, power driven means adapted to be connected to said collecting means to move it toward said holding means upon the interruption of the first mentioned power means, said last named power driven means being operable to return said collecting means to its initial position, and means to automatically interrupt the movements of said collecting means. 5 70
10. In a machine for making radiator units, the combination of means to fabricate an element of said unit, movable means operable in timed relation with said fabricating means to receive and retain a number of said elements as the same are fabricated, automatically operable means to interrupt the movement of said receiving means, automatically operable means to interrupt the fabricating means, means to continue the movement of said receiving means in the same direction while said fabricating means is interrupted, said means for continuing the movement being also operable to move said receiving means in the opposite direction. 20 80
11. In a machine for fabricating a radiator element and assembling the same upon another radiator element, means to receive the fabricated element, and holding means for the other element, said element holding means comprising a two part member, one part being slidable upon the other and having element engaging means thereon, means to lock the two parts together, and means to unlock said parts during a period in the operation of the machine to permit the movement of the slidable part. 30 85
12. In a machine for fabricating a radiator element and assembling the same upon another radiator element, movable means to receive the fabricated element, and holding means for the other element, said element holding means comprising a two part member, one part being slidable upon the other and having element receiving means thereon, means to lock the two parts together, and means to unlock said parts during a period in the operation of the machine to permit the movement of the slidable part, said unlocking means being operable by engagement of said element receiving means therewith. 40 90
13. In a machine for fabricating a radiator element and assembling the same upon another radiator element, movable means for receiving the fabricated element, and holding means for the other element, said element holding means comprising a two part member, one part being slidable upon the other and having means thereon for engaging said second member. 50 95
14. In a machine for fabricating a radiator element and assembling the same upon another radiator element, movable means for receiving the fabricated element, and holding means for the other element, said element holding means comprising a two part member, one part being slidable upon the other and having element engaging means thereon, means to lock the two parts together comprising a pin in one part in engagement with the other part in an opening therein, means engaging said pin and movable to remove said pin from one of said parts to unlock said parts whereby the movement of the slidable part will be permitted. 60 100
15. In a machine for fabricating a radiator element and assembling the same upon another radiator element, movable means for receiving the fabricated element, and holding means for the other element, said element holding means comprising a two part member, one part being slidable upon the other and having means thereon for engaging said second member, means to lock the two parts together comprising a pin in one part in engagement with the other part in an opening therein, means engaging said pin, and means to move said pin engaging means to remove said pin from one of said parts whereby said parts will be unlocked to permit the movement of the slidable part. 70 105
16. In a machine for fabricating a radiator element and assembling the same upon another radiator element, movable means to receive the fabricated element, and holding means for the other element, said element holding means comprising a two part member, one part being slidable upon the other and having means thereon for engaging said second member, means to lock the two parts together, and means to unlock said parts during a period in the operation of the machine to permit the movement of the slidable part, said unlocking means being operable by engagement of said element receiving means therewith, and means associated with said element receiving means and adapted to engage one of said parts to raise the assembled elements from said receiving means. 80 110
17. In a machine for fabricating radiator elements, means to fabricate an element, means to receive the element as fabricated, said means including a pocket adapted to receive the element. 90 115
- 65 120
- 65 125
- 65 130

- ceive the element, and means for retaining the element in said pocket.
18. In a machine for fabricating radiator elements, means to receive a number of the fabricated elements, said means being movable on a support, and means associated with said receiving means and operable by movement thereof to automatically raise the elements therefrom.
19. In a machine for fabricating radiator elements, means to receive the fabricated elements, said means being movable on a support, means associated with said receiving means and operable by movement thereof to automatically raise the elements therefrom, and means to reset said element raising means also operable by movement of said receiving means.
20. In a machine for assembling radiator elements, a pocket adapted to receive a radiator element, means to direct an element into said pocket, and means to urge said element toward said pocket and for preventing rebounding of said element when received in said pocket.
21. In a machine for fabricating radiator elements and assembling the same upon another radiator element, means to receive the fabricated elements comprising a slidable rack having a plurality of element receiving pockets therein, means to operate the fabricating means to move said rack to present a pocket to receive an element as the same is fabricated, means to interrupt the operation of the fabricating means, means to move said rack after said fabricated means is interrupted, and automatically operable means to remove the elements from the pockets in said rack.
22. In a machine for fabricating radiator elements and assembling the same upon another radiator element, means to receive the fabricated elements comprising a slidable rack having a plurality of element receiving pockets therein, means to hold the other element, means to operate the fabricating means and to move said rack toward said other element holding means to present a pocket to receive a fabricated element, means to interrupt the operation of the fabricating means, means to move said rack after said fabricating means is interrupted, means to automatically interrupt the movement of said rack when the elements therein are assembled upon the other element, and automatically operable means to remove the elements from said rack.
23. In a machine for fabricating radiator elements and assembling the same upon another radiator element, means to receive the fabricated elements comprising a slidable rack having a plurality of element receiving pockets therein, means to operate the fabricating means and to move said rack to present a pocket to receive an element as the
- same is fabricated, means to interrupt the operation of the fabricating means, means to move said rack after said fabricating means is interrupted, and automatically operable means to remove the elements from the pockets in said rack, said last mentioned movement of the rack controlling said automatic means, said means to move said rack after said fabricating means is interrupted being also adapted to return said rack to its initial position, and to reset the element removing means.
24. In a machine for fabricating radiator elements and assembling the same upon another radiator element, means to receive the fabricated elements, means to operate the fabricated means and to move the receiving means, means to interrupt the movement of said last named means, means to continue movement of the receiving means, means to return the receiving means to its initial position, and means to automatically control said receiving means moving means.
25. In a machine for fabricating radiator elements, means to receive an element as fabricated, said means having a pocket, and means to insure the rapid movement of said element toward said pocket, including means to provide an air blast directed toward said pocket.
26. In a machine for fabricating radiator elements, means to receive an element as fabricated, said means having a pocket adapted to receive an element, an air blast directed toward said pocket, and means for controlling the flow of air whereby the element will be rapidly moved toward and retained in said pocket.
27. In a machine for making radiator elements, fabricating means, means to collect a number of the elements as the same are fabricated comprising a rack having openings therein to receive the elements, the openings being spaced apart lengthwise of said rack, means to move the rack relatively to said fabricating means, means to hold another element of the radiator, means to move the rack toward the other element to assemble the elements together, and means to raise the assembled elements from the opening in said rack, said last named means comprising lifting means adapted to engage the elements from below, means to raise said lifting means having a downwardly extending member thereon, and means to engage said downwardly extending member to raise the same, said last named means being slidable longitudinally of said rack.
28. In a machine for making radiator elements, fabricating means, means to collect a number of the elements as the same are fabricated comprising a rack having openings therein to receive the elements, the openings being spaced apart lengthwise of said rack, means to move the rack relatively to

said fabricating means, means to hold another element of the radiator, means to move the rack toward the other element to assemble the elements together, and means to raise the assembled elements from the openings in said rack, said last named means comprising lifting means adapted to engage the elements from below, said lifting means having a downwardly extending member thereon, means to engage said downwardly extending member to raise the same, said last named means being slidable longitudinally of said rack, and means secured to said last named means to actuate the same when pressure is applied thereto.

29. In a machine for making radiator units, fabricating means to form an element of said unit, and assembling means to assemble the element to another element of said unit, said assembling means comprising means to collect the fabricated elements, means to hold the other element, means to move the collecting means toward the other element to assemble the elements, means to return the collecting means to its initial position, and automatic controls operable to interrupt the movement of said collecting means at both ends of its movement.

30. In a machine for assembling radiator elements upon a support, means to receive a number of the elements, means to hold the support upon which the elements are to be assembled, means for advancing the element receiving means toward the support to assemble the elements thereon, and means operably associated with said receiving means to release said support holding means and to eject the elements and the support from said receiving means.

40. 31. In a machine for fabricating radiator elements, means to receive a number of the fabricated elements, said means being movable on a support, and means associated with said receiving means to automatically remove the elements therefrom.

32. A machine for making radiator units, comprising means to fabricate an element of said unit, means to collect and retain a number of said elements as the same are fabricated, means to hold another element of said unit, power driven means to drive said fabricating means and to move said collecting means into position to receive said fabricated elements, means to interrupt said driving means, power driven means adapted to be connected to said collecting means to move it toward said holding means during the interruption of said first mentioned power means, said last named power driven means being operable to return said collecting means to its initial position.

33. A machine for making radiator units, comprising means to fabricate an element of said unit, means to collect and retain a number of said elements as the same are fabri-

cated, means to hold another element of said unit, means to drive said fabricating means, means to move said collecting means into position to receive the fabricated elements, means to interrupt the movement of said fabricating means, and power driven means connectable to said collecting means to move it toward said element holding means during the interruption of said fabricating means.

34. In a machine for assembling radiator elements, a slidable member having a pocket adapted to receive a radiator element in said pocket by gravity, and means to assist the action of gravity upon said element.

35. In a machine for assembling radiator elements, a slidable member having a pocket adapted to receive a radiator element in said pocket by gravity, and means continuously operable during the passage of said element to said pocket to assist the action of gravity upon said element, and to insure a rapid movement of said element toward said pocket.

36. A machine for making radiator units, comprising means to fabricate an element of said unit, means to collect and retain a number of said elements as the same are fabricated, power driven means to drive said fabricating means and to move said collecting means into position to receive said fabricated elements, means to interrupt said driving means, power driven means adapted to be connected to said collecting means to move it in a direction opposite to the direction of its movement into element receiving position, during the interruption of said first mentioned power means, means to support another element of said unit, said second mentioned power driven means being adapted to move said receiving means toward said element supporting means to assemble the elements together.

37. A machine for making radiator units, comprising means to fabricate an element of said unit, means to collect and retain a number of said elements as the same are fabricated, power driven means to drive said fabricating means and to move said collecting means into position to receive said fabricated elements, means to interrupt said driving means, power driven means adapted to be connected to said collecting means to move it in a direction opposite to the direction of its movement into element receiving position during the interruption of said first mentioned power means, means to support another element of said unit, said second mentioned power driven means being adapted to move said receiving means toward said element supporting means to assemble the elements together.

50 115 120 125 130

38. A machine for making radiator units,

comprising means to fabricate an element of said unit, means to collect and retain a number of said elements as the same are fabricated, power driven means to drive said fabricating means and to move said collecting means into position to receive said fabricated elements, means to interrupt said driving means, power driven means adapted to be connected to said collecting means to move it in a direction opposite to the direction of its movement into element receiving position during the interruption of said first mentioned power means, means to support another element of said unit, said second mentioned power driven means being adapted to move said receiving means toward said element supporting means to assemble the elements together, and means on said supporting means engageable by said receiving means to release therefrom the elements held thereby, and means operably associated with said receiving means to eject the elements therefrom.

39. A machine for making a radiator unit, comprising means to fabricate an element of said unit, movable means to collect a number of said elements, said means being adapted to assemble said elements to another element of said unit, means to interrupt the movement of said collecting means, and means to continue the movement thereof in the same direction.

40. A machine for making a radiator unit, comprising means to fabricate an element of said unit, intermittently movable means to collect a number of said elements, said collecting means being adapted to assemble said elements to another element of said unit, means to interrupt the intermittent movement of said collecting means, and means to cause a continuous movement thereof in the same direction.

41. In a machine for making a radiator unit, means to fabricate an element of said unit, movable means to collect a number of said elements and to assemble them to another element of said unit, and means to substantially simultaneously interrupt said fabricating means and the movement of said collecting means.

42. In a machine for making a radiator unit, means to fabricate an element of said unit, movable means to collect a number of said elements and to assemble them to another element of said unit, means to substantially simultaneously interrupt said fabricating means and the movement of said collecting means, and means to continue the movement of said collecting means in the same direction.

43. In a machine for making a radiator unit, means to fabricate an element of said unit, movable means to collect a number of said elements and to assemble them to another element of said unit, means to substan-

tially simultaneously interrupt said fabricating means and the movement of said collecting means, means to continue the movement of said collecting means in the same direction, and means operated by the continued movement of said last named means to eject said elements from said collecting means.

44. In a machine for making a radiator unit, means to fabricate an element of said unit, movable means to collect a number of said elements and to assemble them to another element of said unit, means to substantially simultaneously interrupt said fabricating means and the movement of said collecting means, means to continue the movement of said collecting means in the same direction, means operated by the continued movement of said last named means to eject said elements from said collecting means, and means to return said collecting means to its initial position.

45. In a machine for making a radiator unit, means to fabricate an element of said unit, movable means to collect a number of said elements and to assemble them to another element of said unit, means to substantially simultaneously interrupt said fabricating means and the movement of said collecting means, means to continue the movement of said collecting means in the same direction, means operated by the continued movement of said last named means to eject said elements from said collecting means, means to return said collecting means to its initial position, and means to reset said collecting means operated by the return movement of said collecting means to permit the collection of more of said elements.

46. In a machine for making a radiator unit, means to fabricate an element of said unit, movable means to collect a number of said elements and to assemble them to another element of said unit, and automatically operable means to interrupt the movement of said collecting means when the same has received a predetermined number of elements.

47. In a machine for making a radiator unit, means to fabricate an element of said unit, movable means to collect a number of said elements and to assemble them to another element of said unit, and automatically operable means to interrupt the movement of said collecting means after a predetermined number of said elements collected thereby have been assembled to said other element of said unit.

48. In a machine for making a radiator unit, means to fabricate an element of said unit, element collecting means, means to direct said elements from said fabricating means to said collecting means, and means to urge said elements rapidly through said directing means.

49. In a machine for making a radiator unit, means to fabricate an element of said unit, element collecting means, means to direct said elements from said fabricating means to said collecting means, and means to urge said elements rapidly through said directing means and into said collecting means, said urging means continuing to operate upon said elements to prevent rebounding thereof from said collecting means.

10 In witness whereof, I have hereunto set my hand this 19th day of January, 1927.

DANIEL I. ROGERS.
